UNITED STATES PATENT OFFICE.

ISADORE DAVIS, OF DES MOINES, IOWA, ASSIGNEE TO INTERLOCKING SHINGLE CO., OF DES MOINES, IOWA, A CORPORATION OF IOWA.

INTERLOCKING MULTIPLE SHINGLE.

Application filed May 15, 1925. Serial No. 30,638.

The object of this invention is to provide an improved interlocking shingle of asphalt, composition or other flexible or partially flexible character.

5 A further object of this invention is to provide improved means for interlocking flexible shingles of multiple or strip form.

10 A further object of this invention is to provide improved means for causing flexible shingles to lie flat on a roof without the use of many nails.

A further object of this invention is to provide an improved form of interlocking clip for shingles.

15 A further object of this invention is to provide improved means for protecting the edges of shingles and also preventing the entrance of the elements when they are laid on a roof.

20 With these and other objects in view, my invention consists in the construction, arrangement and combination of elements hereinafter set forth, pointed out in the claims and illustrated by the accompanying drawing, in which—

Figure 1 is a perspective view of a double shingle embodying my improvements. Figure 2 is a perspective view showing the lower face of one of the interlocking loops adapted to be mounted on the upper face of a shingle. Figure 3 is a perspective view showing the lower side of one of the hooks adapted to be mounted on the lower side of a shingle and to interlock with the loop shown in Figure 2. Figure 4 is a plan view showing a section of roofing formed by my improved shingles. Figure 5 is a section on the line 5—5 of Figure 4, on an enlarged scale. This improvement relates to improved means for laying flexible or semi-flexible shingles, which are ordinarily made of felt or composition and provided with a fire-proofing coating of asbestos or other suitable material, and it relates more particularly to such shingles which are of multiple character, that is to say a strip presenting the appearance of two or more individual shingles.

In the construction of the shingle as shown 30 the numeral 10 designates a substantially rectangular body which may be of any suitable length, and provided on its lower margin with projections 11, 12, in this instance two in number and substantially triangular in shape. On the upper surface of the body

10, and arranged near its top margin and centrally of the points 11, 12, are loop members of the interlocking devices, one for each of the points 11, 12. Each loop member comprises a body 13 having teeth 14 projecting from its lower face adapted to be inserted through and clinched relative to the body of the shingle. The body of the clip 13 is slotted transversely at 15 and a portion centrally of said body and just above said slit 65 is pressed upwardly to form a loop or keeper 16 open at its lower margin. If desired the central portion of the loop or keeper 16 may be cut out and pressed downwardly to form a tongue 17 free at its lower margin, for a 70 purpose which will be hereinafter made clear. Above the loop or keeper 16, the body of the clip is formed with a transverse slot 18 adapted to receive a nail for attaching the shingle to a roof. The keeper clip just described is shown particularly in Figure 2, 75 in inverted position.

In Figure 3 I have shown a clip adapted to cooperate and interlock with the keeper clip above described, which comprises a 80 substantially rectangular body 19 formed with projecting teeth 20 by means of which it may be firmly attached to the shingle. On one margin the clip 19 is provided with an integral projection or lug 21, preferably substantially semi-circular in outline, the main portion of which is in about the same plane as the body of the clip. The central portion of the lug 21, however, is pressed or indented to concavo-convex form at 22, in the same 85 direction as that in which the teeth 20 project, in other words toward the shingle when the clip is attached. One of the clips 19 is placed on the lower surface of each projection 11, 12 of the shingle, near the apex 95 thereof, and arranged with the lug 21 pointing toward the top of the shingle and upwardly of the roof when the shingle is in place.

In practical use a course of the shingles 100 are laid end to end, preferably with a slight space between them as indicated in Figure 4, and one nail is driven through the slot 18 of each clip 13 into the roof, as indicated at 93 in said Figure 4. Then another course 105 is superposed on the course so laid, the lugs 21 of such superposed course being first inserted by upward movement into the downwardly opening keepers 16 of the clips 13 on the lower course, and then nails are 110

driven through the slots 18 of the superposed course. The interlocking clips serve to guide the workmen in laying the shingles, but also they serve to securely interlock the successive courses of shingles and to hold them securely to the roof, only one nail being used for each unit of the multiple shingle. The indented portion 22 of the lug 21 serves, by contact with the lower face of the shingle 19 on which the clip 19 is placed, to hold the margin of said lug away from the surface of the shingle and facilitate its entrance to the loop or keeper 16, and when inserted, such indented portion tends to contact rather forcibly with the adjacent wall of said keeper. Where the tongue 17 is employed, as in Figures 2 and 5, the lug 21 extends between said tongue and the top wall of the keeper, and the frictional contact is further increased in the interest of stability of engagement; but it is to be understood that this tongue is not necessary to the successful operation of my interlocking clips.

The substantially triangular projections 11, 12 of each shingle are exposed to the weather, together with similar portions of the bodies lying between the projections of superposed shingles, thus presenting a diamond-shaped arrangement as shown in Figure 4.

If desired, the body 10 of each shingle may be formed with a rectangular aperture 24 near the angle between the projections 11, 12, as well as with lateral notches 25, 26 at its ends near the bases of said projections, to receive the clips 13 so that the shingles are not caused to bulge by said clips.

In the process of the manufacture of the shingle, it is formed with a sealed edge or crimped margin 27 as shown in Figure 5 particularly, extending entirely around such portion as is to be exposed when the shingle is laid. In order to prevent breakage of the shingle in producing such crimped margin, as would occur if it were merely bent forcibly, it is treated in the presence of live steam, the heat and moisture permitting the material to be pressed together and to close the pores, so that it becomes more compact, is reinforced and a finished edge is produced which tends to prevent the passage of moisture between the shingles, also causes them to lie better on the roof because the edge is made heavier. In this operation the marginal portion is caused to assume a position substantially at right angles to the plane of the shingle, the portion immediately adjacent such marginal portion being bulged away from the plane of the shingle to form a thickened portion as shown in Figure 5.

The relative placing of adjacent shingles,

as well as the relation of the clips 13, 19 to each other, and of the clips 13 to the nails 23 by means of the slots 18, permits of some movement to compensate for expansion and contraction of the material of the shingles due to changes in temperature, so that the collocation of shingles always lies flat to the roof surface.

When the roof is laid, the apertures 24, 70 as well as the clips and other fastening means, are covered, protected and concealed by the projections 11 and 12.

I claim as my invention—

1. A shingle formed of flexible material 75 and comprising a body and a projection on its lower margin, said body being formed with an aperture adjacent the base of said projection, a keeper clip fixed to the upper surface of said body, and a clip fixed to the 80 lower surface of said projection and adapted to engage and interlock with the keeper clip of a subjacent shingle, which keeper clip is exposed through the body aperture of an intermediate shingle. 85

2. A shingle formed of flexible material and comprising a body and a plurality of projections on its lower margin, keeper clips fixed to the upper surface of said body, and a clip attached to the lower surface of each 90 of said projections and adapted to engage and interlock with a keeper clip of a subjacent shingle, said body being formed with an aperture on a line midway between its 95 projections to receive the interlocked clips of adjacent shingles.

3. A shingle formed of flexible material, a keeper clip fixed to the upper surface of said shingle and pressed upwardly in its central portion to form a downwardly opening loop or keeper, a tongue struck out from the material of said loop and projecting toward the open end thereof, and a clip fixed to the lower surface of said shingle and having an upwardly directed lug adapted to enter the loop or keeper of a subjacent shingle and to engage the tongue thereof. 100

4. A shingle formed of flexible material, a keeper clip fixed to the upper surface of said shingle and pressed upwardly in its central portion to form a loop or keeper, a clip fixed to the lower surface of said shingle and formed with an upwardly directed lug, a portion of said lug being pressed toward the plane of the shingle, said lug adapted 110 to engage and frictionally interlock with the loop or keeper of a subjacent shingle. 115

Signed at Des Moines, in the county of Polk and State of Iowa, this 3rd day of February, 1925.

ISADORE DAVIS.
